CONTAINER CAP

Robert P. Vuillemenot, Oradell, N.J., assignor to The Procter & Gamble Company, Cincinnati, Ohio, a corporation of Ohio

Filed Aug. 8, 1968, Ser. No. 13,071

Term of patent 14 years

Int. Cl. D9—02

U.S. Cl. D9—284

Fig. 1

Fig. 3

I claim:

The ornamental design for a container cap, as shown.
